UNITED STATES PATENT OFFICE.

JACOB WILLIAM LATTIG, OF GLENSIDE, PENNSYLVANIA, ASSIGNEE, BY MESNE ASSIGNMENTS, OF ONE-HALF TO MITCHELL H. WOODHULL, OF NEW YORK, N. Y., AND ONE-HALF TO ARTHUR C. HUTCHESON, OF BOUND BROOK, NEW JERSEY.

GASEOUS-FUEL MIXER.

1,233,256.

Specification of Letters Patent. Patented July 10, 1917.

Application filed May 22, 1913. Serial No. 769,124.

To all whom it may concern:

Be it known that I, JACOB WILLIAM LATTIG, a citizen of the United States, and a resident of Glenside, in the county of Montgomery and State of Pennsylvania, have invented certain new and useful Improvements in Gaseous-Fuel Mixers, of which the following is a specification.

The invention relates to improvements in gaseous fuel engines, adapted to utilize gasoline or other hydrocarbon fuel and in which the said fuel is first vaporized in the presence of air and then supplied to the cylinders. Its objects are, among others, to provide a device adapted to be interposed between the carburetor and the engine cylinder and to act upon the mixture of air and hydrocarbon vapor—commonly called “gas”—in such a manner as to regulate, control and auxiliate the same and thereby effect an economy of fuel, prevent fouling or carburization of the cylinders and ignition devices, prevent back-firing and insure the easy starting and smooth running of the engine.

It is a well known fact that in engines of the character indicated, and particularly those used for the propulsion of automobiles a considerable percentage of the fuel is wasted, and that this waste of fuel is not only a great expense but causes fouling of the cylinders and other parts as well as other undesirable results.

Another difficulty is in starting the engine when the parts are cold and the gasoline does not volatilize rapidly, and still another serious objection is the smoke caused by such engines.

The present improvements do not relate to the carburetor, nor yet to the engine, although they have a direct bearing on both, and contemplate a certain arrangement and relationship to both. They reside essentially in the provision of a diaphragm or partition and an absorbent capillary body, so constructed and arranged as to permit the relatively free passage of fuel “gas” therethrough and at the same time receive and hold small particles of liquid and present them for vaporization at all times, and particularly when the percentage of vapor falls below a certain point, thus insuring a uniform mixture and also supplying

vapor at times when the supply from the carburetor is not adequate or satisfactory. 55 This device is located between the carburetor and the engine, and its peculiar functions are such that it must be substantially separate and distinct from both.

It is illustrated in the accompanying 60 drawings in which Figure 1 is a view partly in elevation and partly in section of a device located between a carburetor and manifold pipe embodying the improvements. Fig. 2 is a plan view (looking upward from 65 the carburetor) of the device on an enlarged scale, and Fig. 3 is a view in cross section on the line 3—3 of Fig. 2 with the device reversed from the position shown in Fig. 1. Fig. 4 is a view similar to Fig. 3, showing 70 a modification.

1 represents a carburetor and 2 a manifold pipe, and the improved device is secured between the manifold pipe 2 and the outlet of the carburetor.

The manifold pipe 2 has an annular flange 3 on its end, and the outlet of the carburetor is made with a flange 6, said flanges having registering openings therein for the reception of bolts 5, so that when 80 the device is positioned between the flanges 3 and 6, the bolts 5 may be projected through said flanges and secured by nuts 4 and 7 to securely clamp the device between them.

The device comprises a metal ring composed of a connecting portion 8 with inwardly extending flanges 9 and 10 giving it a U-shape in cross-section, a disk of porous metal 12 and an annulus of absorbent material 11 clamped between the flanges 9 and 10, and the whole forming a diaphragm or partition spanning the bore of the pipe 2. The metal disk is composed of woven wire netting, and this is the preferred construction. It may, however, be made in some other suitable form, as it is only necessary that it shall be relatively rigid and shall present a suitable number of openings through which the vapor may pass, and preferably of a size small enough to prevent back fire. The absorbent material 11 is made in the form of an annulus in order to leave the central portion of the metal disk free and unobstructed thereby. 100 If desired, however, the absorbent material

may also be made in some other suitable form which will permit the free passage of vapor therethrough to the desired extent.

- The diaphragm 12 acts as a screen and 5 not only breaks up the vapor charged air passing therethrough, but retards it and agitates it to a certain extent, and the absorbent 11, which is of some soft capillary material, preferably fibrous, acts as a wick to absorb 10 and break up the particles of liquid in the mixture and hold them by capillary action so that it will provide a basis of vaporization and act as an equalizer of the strength of the mixture.
- 15 The ring composed of the flanges 9 and 10 and connecting portion 8 is clamped between the flanges 3 and 6, as hereinbefore described, and the space inclosed by the said ring is of greater diameter than the passage 20 from the carbureter to the manifold pipe, so that the metal ring does not obstruct the passage, and gives to the partition consisting of the wick 11 and metal diaphragm 12 a maximum area of exposed surface. The 25 flange 9 is provided with an annular flange 13 turned substantially parallel with the conduit between the carbureter and the manifold, the purpose of which is to fix the position of the device and hold it 30 in place by engaging the inner walls of said conduit. This flange is on the side of the device nearest the carbureter, and it will be understood that the absorbent is also preferably on that side, so as to be protected 35 by the screen 12 from the engine. This is important when the absorbent is made of inflammable material instead of asbestos or some other non-inflammable absorbent.

- In operation, the wick becomes saturated 40 with the gasolene, and presents an extended surface through which the gas passes to the cylinders, but holds back and absorbs any globules or particles—due to imperfect vaporization, condensation or other cause— 45 which would otherwise pass to the cylinders and present them in the proper manner for vaporization and mixture with air.

- In the modification of Fig. 4 the screen 14 is given a truncated conical form at the 50 center and at the apex. On the side next to the carbureter, is a disk of absorbent material 15, sewn or otherwise secured to the screen. With this construction some of the 55 particles of liquid rushing through the conduit will strike the oblique sides of the cen-

tral cone at an acute angle and have a tendency to break up and deflect in the direction of the central absorbent disk 15, while the others will strike the absorbent 15 and be absorbed and broken up thereby.

While I have illustrated and described a preferred form of the invention, it will be apparent that various immaterial changes may be made in the general form and arrangement of parts described without departing from the invention, and hence I do not limit myself to the precise details set forth, but consider myself at liberty to make such changes and alterations as fairly fall within the spirit and scope of the appended claims.

What I claim is:

1. A device of the character described adapted to be located in the conduit between a carbureter and an engine cylinder, comprising a partition of metal with openings therein, an absorbent supported by said partition and a hollow metal ring inclosing the outer edges of the partition and the absorbent and the surfaces thereof adjacent to said outer edges, and a flange extending from the inner edge of said hollow metal ring in a direction substantially parallel with the adjacent walls of the conduit.

2. The combination of a metal frame and an absorbent, said absorbent being located at different points longitudinally in the conduit between the carbureter and the engine cylinder and having an opening therein adapted to permit the free passage of fluid.

3. The combination of a metal frame and an absorbent, said absorbent being located in the interior of the metal frame and spaced from the outer edges of said metal frame so that the gaseous fuel may pass between it and the walls of the conduit in which the device is located.

4. In an article of manufacture, a gasket; a gauze container having a marginal flange embodied in the gasket; and porous material in the container positioned to leave an annular space about the porous material in the container.

Witness my hand this 28th day of April, 1913, at the city of New York, in the county and State of New York.

JACOB WILLIAM J. ATTIG.
